UNITED STATES PATENT OFFICE.

HENRY A. FRENCH, OF LANSING, MICHIGAN.

DESIGN FOR A PUMP-STANDARD.

SPECIFICATION forming part of Design No. 26,869, dated April 6, 1897.

Application filed January 25, 1897. Serial No. 620,697. Term of patent 14 years.

To all whom it may concern:

Be it known that I, HENRY A. FRENCH, a citizen of the United States, residing at Lansing, in the county of Ingham and State of Michigan, have invented and produced a new and original Design for Pumps, of which the following is a specification, reference being had therein to the accompanying drawings, in which—

10 Figure 1 is a perspective view of the pump-standard, showing my design. Fig. 2 is a rear elevation thereof.

The leading feature of my design is the configuration of the standard.

15 B is a flat foot or base of substantially rectangular shape with rounded corners. Centrally of the base B is a short cylindrical collar. From each corner of the base extends toward the collar C a web D, having a curved 20 upper edge, as shown. From the collar C rises the plain cylindrical standard A, provided near its top with a cylindrically-enlarged portion E, having near its upper and

lower edge a band F and at one side between said bands the rounded projections G. Above 25 this collar is the pump-top. This top has a bottom ring H, above which is a horizontally-disposed cylindrical enlargement I with plain flat ends, from one side of which projects the gooseneck J, banded as shown. Projecting 30 from the top is the round tapering chamber K, having the curved dome-shaped top L, terminating in a cylindrical nipple M. This chamber K has the bands *a b*, and extending 35 from the front of the top is the cup-shaped projection *c*.

What I claim as my invention is—

The design for a pump-standard substantially as herein described and shown.

In testimony whereof I affix my signature 40 in presence of two witnesses.

HENRY A. FRENCH.
